CLAIM

The ornamental design for a plumbing spout, as shown and described.

DESCRIPTION

FIG. 1 is a top perspective view of a plumbing spout showing my new design;

FIG. 2 is a front elevational view thereof;

FIG. 3 is a rear elevational view thereof;

FIG. 4 is a right side elevational view thereof, the left side being a mirror image of the right side shown.

FIG. 5 is a top plan view thereof;

FIG. 6 is a bottom plan view thereof; and

FIG. 7 is a right side elevational view of a modified form of the plumbing spout shown in FIG. 1, the left side being a mirror image of the right side shown.

The fragmentary broken line representations of openings in FIGS. 1, 2, 5 and 6 are for purposes of illustration only.

FIG. 1

FIG. 2

FIG. 3
